PHOSPHATIDIC COMPOSITION

Benjamin H. Thurman, Bronxville, N. Y., assignor
to Refining, Inc., Reno, Nev., a corporation of
Nevada

No Drawing. Application December 29, 1939,
Serial No. 311,705

16 Claims. (CL 260—403)

This invention relates to phosphatidic compositions, and more particularly to compositions resulting from treating phosphatides with alkali metal phosphates.

In my copending application Serial No. 290,083, filed August 14, 1939, of which this application is a continuation in part, I have disclosed compounds or compositions resulting from reacting phosphatides with various alkali metal salts, among which was a compound of sodium phosphate (Na_2PO_4) with phosphatides. When sufficient sodium phosphate is employed to react with substantially all of the phosphatides, a resulting compound which is alkaline, that is, a compound which gives a pH substantially in excess of 7 when dissolved in water, is produced. In accordance with the present invention, I have found that alkali metal phosphate-phosphatide compounds which are substantially neutral or somewhat acidic, are much more stable than similar compounds which are alkaline. The neutral or acidic compounds can be prepared by employing alkali metal phosphates such as disodium phosphate, monosodium phosphate, etc., which have a lesser amount of alkali metal in their molecule than the normal sodium phosphate. Also, mixtures of various metal phosphates may be employed to obtain a desired pH. In general, the greater the amount of alkali metal in the molecule and the greater the alkalinity of the metal, the more alkaline the resulting phosphatidic composition. The resulting products appear to be true chemical compounds from all the physical and chemical evidence available.

It is, therefore, an object of the invention to provide an improved alkali metal phosphate-phosphatidic composition having increased stability.

Another object of the invention is to provide an alkali metal phosphate-phosphatidic composition having neutral or acidic properties.

A further object of the invention is to provide an improved alkali metal phosphate-phosphatidic composition having high stability against decomposition, said composition resulting from the treatment of phosphatides with a mixture of alkali metal phosphates so as to produce a neutral or acidic product.

A still further object of the invention is to provide a process of producing alkali metal phosphate-phosphatidic compositions having neutral or acidic properties.

Other objects and advantages of the invention will appear in the following description of preferred embodiments thereof.

Although phosphates of any of the alkali metals may be employed, the invention will be specifically described with respect to various sodium phosphates. As stated above, the normal or trisodium phosphate produces a compound which is distinctly alkaline when combined with phosphatides. It has been found that the alkalinity of the compound increases with temperature of reaction and time of reaction up to a pH of approximately 10.5 even though excess alkali is separated from the compound. On the other hand, by employing a salt containing a lesser amount of alkali metal in the molecule such as monosodium phosphate, compounds having a pH as low as 4.5 can be produced. In general, the acid phosphates of alkali metals, that is to say, phosphates which have one or more hydrogens replacing an alkali metal, produce acid or at least neutral compounds with phosphatides. Also, phosphates which have less than three alkali metal atoms for each phosphate group such as the acid phosphates or such salts as the meta or hexamets phosphates produce neutral or acidic compounds. By employing various mixtures of salts such as mixtures of trisodium phosphate and disodium phosphate, mixtures of trisodium phosphate and monosodium phosphate, and mixtures of disodium phosphate and monosodium phosphate, a compound having a desired pH between the limits above given can be produced. It has been found that phosphate-phosphatide compounds which are strongly alkaline, for example, having a pH in the neighborhood of 10.5, are quite unstable and will even split into the phosphate and phosphatide if allowed to stand at ordinary temperatures. Poor stability appears to begin at a pH of 7.8, that is to say, compounds having a pH of 7.8 and lower are stable, for example as measured by the Schaal method at 70° C. for rancidity. The acid and substantially neutral products showed no rancidity after being heated at this temperature for many hours, while the more alkaline compounds rapidly decompose into products giving off amine-like odors.

Disodium phosphate alone when reacted with phosphatides produces a substantially neutral compound. As a specific example of employing this material, 100 gr. of corn phosphatides were thoroughly mixed with a solution containing 25 gr. of anhydrous disodium phosphate and 60 cc. of water. The reaction mass was stirred for one hour at room temperature and dehydrated in vacuo for 2½ hours at 65 to 100° C. When the water in the dehydrated mass had been reduced

to approximately 1%, a pasty material remained. The paste was extracted with petroleum ether and the ether extract subjected to vacuum treatment to remove the ether. The resulting product was a clear, amber, viscous, oily material which was odorless and had a slightly salty taste.

The original purified corn oil phosphatide had a phosphorus content of approximately 2.1%, a nitrogen content of approximately 1.2% and a pH of approximately 4.6 when dispersed in water; whereas the resulting compound had a sodium content of 5.7%, a phosphorus content of 4.8%, a nitrogen content of approximately .9%, and a pH of approximately 7.

Sodium hexametaphosphate also forms a compound with phosphatides which is substantially neutral. As a specific example of making such a compound, 75 gr. of the corn phosphatide above referred to was mixed with 35 gr. of sodium hexametaphosphate in 70 gr. of water, stirred for 3 hours at room temperature, and dehydrated at 65° C. for 18 hours in vacuo. This compound is unique in that, instead of an opaque paste-like mixture being formed, the reaction mass is a clear, viscous oil very soluble in water. If desired, the oily material may be extracted with ether as described in the previous example in order to remove excess alkali or other unreacted products, and the resulting compound had a sodium content of 5.8%, a phosphorus content of 6.2%, and produced a pH of 7.1.

The pH of the products of either of the above two examples may be made smaller by employing a mixture of monosodium phosphate and disodium phosphate in the first example and a mixture of monosodium phosphate and sodium hexametaphosphate in the second example. As stated above, the acid and neutral compounds are extremely stable. However, if desired, the products of the two examples above given may be made more alkaline by employing mixtures of the disodium phosphate or sodium hexametaphosphate with trisodium phosphate.

Other sodium phosphates may be employed, for example sodium metaphosphate and sodium pyrophosphate either alone or in admixture with any of the other phosphates herein mentioned to produce compositions having any desired pH. The products disperse in oil in the cold, and dissolve in oil when heated to about 90° F., to give a clear solution which has a powerful emulsifying action toward water. They are soluble in ether and dispersable in water. The equivalent salts of potassium or other alkali metals may be employed instead of sodium salts to give similar results.

Phosphatides other than the corn phosphatides mentioned may likewise be employed to form the compounds of the present invention. Corn phosphatides are preferred, as they are light in color and contain no linolenic acid radicals, thereby being more stable than such phosphatides as soya bean phosphatides. Furthermore, the soya bean phosphatides are much darker in color and are likely to become still further colored if subjected to heat. Cottonseed phosphatides may also be employed, and produce compositions of high stability, but are usually quite highly colored. The corn phosphatides are somewhat more acidic than soya bean phosphatides. Thus, corn phosphatides usually produce a pH between 4.5 and 4.8 when dispersed in water, while soya bean phosphatides produce a pH in the neighborhood of 5.7. It has been found that the corn phosphatides take up more

5 sodium and phosphorus than those from soya bean phosphatides. It is believed that the reaction between the sodium phosphate employed and the phosphatide is an acid-base combination and that the more acidic material (corn phosphatides) reacts with larger amounts of the basic material, although applicant does not wish to be bound by any precise theory of combination, as the chemistry is extremely complex.

10 The compounds or compositions of the present invention, particularly those having acid characteristics and greater stability, are useful as emulsifying agents for oil and water emulsions. All of the compounds mentioned are edible and can be employed in edible products. For example, they can be employed in the production of mayonnaise or margarine to retain water, emulsified with the oils or fats. Phosphatides which are free of linolenic acid radicals such as corn and cottonseed phosphatides are preferred for use in edible products as they have no tendency to revert to an undesirable taste as is the case of soya bean phosphatidic compounds, which have a tendency to revert to the original flavor and odor of the soya bean oil. The compositions of the present invention with soya bean phosphatides are, however, more stable than the original soya bean phosphatides. The compounds of the present invention are particularly valuable in producing high ratio shortening for baked products; that is to say, a small amount thereof, for example 25 to 5% and usually about 2% on the basis of the shortening, will enable ratios of sugar to flour in excess of one-to-one to be employed in cakes having increased volume and excellent texture.

15 The compositions of the present invention are also useful as constituents in detergents, since they have excellent emulsifying properties and are compatible with all common detergent materials. They also have extremely good water softening properties, particularly compositions including substantial amounts of the hexametaphosphate. They may be employed with alkali metal soaps to produce hard water soaps by preventing precipitation or decomposition of insoluble alkali earth metal soaps such as those of calcium or magnesium. Smooth, stable emulsions of vegetable, mineral or essential oils with water are obtained when small amounts, for example 1 to 5% of the composition referred to are added to either the water or oil phase and the resulting mixture thoroughly agitated. The compositions may also be blended with ingredients of salves, ointments, face creams, shaving creams, nose drops, nose sprays, etc., to produce smoother products having greater water retention properties. They are of value in insecticidal emulsions to prevent separation of the components thereof and to cause said emulsions to spread when applied. The compositions of the present invention also have utility as pigment dispersing agents for oil paints and as emulsifiers in casein paints. Other uses of the compositions are as emulsifiers in flotation processes, surface tension reducing agents in textile treatment, and wherever emulsifying or surface tension reducing agents are desired.

20 While, for the want of a better term, I have herein referred to my new chemical compounds as "phosphatidic compounds," it is nevertheless to be understood that the same are fundamentally dissimilar in composition, behavior and utility to the usual soy bean lecithin of commerce.

25 While I have disclosed the preferred embodiment

ments of my invention, it is understood that the details thereof may be varied within the scope of the following claims.

I claim:

1. As a product of manufacture, an alkali metal phosphate-phosphatidic composition having high stability and a pH when dispersed in water not substantially greater than 7.8, said compound resulting from reacting a phosphatide with a mixture of alkali metal phosphates, said mixture having substantially less than three alkali metal atoms for each phosphate group.
2. As a product of manufacture, an alkali metal phosphate-phosphatidic composition having high stability and a pH when dispersed in water not substantially greater than 7.8, said compound resulting from reacting a phosphatide with an alkali metal phosphate having less than 3 atoms of alkali metal for each phosphate group.
3. As a product of manufacture, an alkali metal phosphate-phosphatidic composition having high stability and a pH when dispersed in water not substantially greater than 7.8, said compound resulting from reacting a phosphatide with an acid alkali metal phosphate.
4. As a product of manufacture, an alkali metal phosphate-phosphatidic composition having high stability and a pH when dispersed in water not substantially greater than 7.8, said compound resulting from reacting a phosphatide with a mixture of alkali metal phosphates including a substantial quantity of an acid phosphate.
5. As a product of manufacture, an alkali metal phosphate-phosphatidic composition having high stability and a pH when dispersed in water not substantially greater than 7.8, said compound resulting from reacting a phosphatide with a mixture of alkali metal phosphates including a substantial quantity of a monophosphate.
6. As a product of manufacture, an alkali metal phosphate-phosphatidic composition having high stability and a pH when dispersed in water not substantially greater than 7.8, said compound resulting from reacting a phosphatide with a sodium phosphate having less than 3 atoms of alkali metal for each phosphate group.
7. As a product of manufacture, an alkali metal phosphate-phosphatidic composition having high stability and a pH when dispersed in water not substantially greater than 7.8, said compound resulting from reacting a phosphatide with disodium phosphate.
8. As a product of manufacture, an alkali metal phosphate-phosphatidic composition having high stability and a pH when dispersed in water not substantially greater than 7.8, said compound resulting from reacting a phosphatide with monosodium phosphate.
9. As a product of manufacture, an alkali metal phosphate-phosphatidic composition having high stability and a pH when dispersed in water not substantially greater than 7.8, said compound resulting from reacting a phosphatide with sodium hexametaphosphate.
10. As a product of manufacture, an alkali metal phosphate-phosphatidic composition having high stability and a pH when dispersed in water not substantially greater than 7.8, said compound resulting from reacting a phosphatide which is free of linolenic acid radicals with a sodium phosphate having less than 3 atoms of alkali metal for each phosphate group.
11. As a product of manufacture, an alkali metal phosphate-phosphatidic composition having high stability and a pH when dispersed in water not substantially greater than 7.8, said compound resulting from reacting a corn phosphatide with a sodium phosphate having less than 3 atoms of alkali metal for each phosphate group.
12. The process of producing phosphatidic compounds containing alkali metals and having high stability, which comprises, reacting a phosphatide in the presence of water with an alkali metal phosphate having less than 3 alkali metal atoms for each phosphate group and dehydrating the resulting product.
13. The process of producing phosphatidic compounds containing alkali metals and having high stability, which comprises, reacting a phosphatide in the presence of water with a mixture of alkali metal phosphates said mixture having substantially less than 3 alkali metal atoms for each phosphate group, dehydrating the resulting reaction products, extracting said compound from said reaction products with a solvent therefor, and evaporating said solvent from said compound.
14. The process of producing a sodium phosphate-phosphatidic compound, which comprises, reacting a phosphatide in the presence of water with a sodium phosphate containing less than 3 sodium atoms for each phosphate group, dehydrating the resulting reaction products, extracting said compound from said reaction products with a solvent for said compound, and evaporating said solvent from said compound.
15. The process of producing sodium phosphate-phosphatidic compounds having high stability, which comprises, reacting sodium hexametaphosphate in the presence of water with a phosphatide, and dehydrating the resulting product.
16. The process of producing phosphatidic compounds containing alkali metals and having high stability, which comprises, reacting a phosphatide in the presence of water with a mixture of alkali metal phosphates containing a substantial portion of a monophosphate, and dehydrating said product.

BENJAMIN H. THURMAN.
